[57] CLAIM

The ornamental design for a telephone support stand, and described.

DESCRIPTION

FIG. 1 is a front, top and partial right side perspective view of a telephone support stand showing my new design;

FIG. 2 is a front elevation thereof;

FIG. 3 is a top plan view thereof;

FIG. 4 is a bottom plan view thereof;

FIG. 5 is a right side elevation thereof, the left side elevation being a mirror image; and

FIG. 6 is a rear elevation thereof.
